UNITED STATES PATENT OFFICE.

WILLIAM R. COLE, OF DETROIT, MICHIGAN.

PLUG-SWITCH.

SPECIFICATION forming part of Letters Patent No. 591,126, dated October 5, 1897.

Application filed March 11, 1897. Serial No. 626,973. (No model.)

To all whom it may concern:

Be it known that I, WILLIAM R. COLE, a citizen of the United States, residing at Detroit, in the county of Wayne and State of Michigan, have invented certain new and useful Improvements in Plug-Switches, of which the following is a specification, reference being had therein to the accompanying drawings.

10 It is the object of my invention to produce a simple form of plug-switch which is especially adapted for use in multiple switchboards, where it is of the utmost importance to secure the greatest economy of space.

15 The invention consists in the peculiar construction, arrangement, and combination of parts, as more fully hereinafter described.

In the drawings, Figure 1 is a perspective view of a portion of a switchboard to which 20 my invention is applied, together with one of the plugs. Fig. 2 is an enlarged section thereof, showing one of the sockets and the plug. Fig. 3 shows the sheet-metal blanks from 25 which the sockets are formed. Fig. 4 is a perspective view of said sockets when formed, and Fig. 5 is a perspective view of said sockets secured in the insulator-plates.

My switch comprises two plates A A', of insulating material, arranged parallel to each 30 other, each being provided with a series of corresponding registering apertures B B'.

C C' are metallic sockets secured in the apertures B B', which are preferably formed as follows: Blanks are first cut out of sheet 35 metal and shaped as shown in Fig. 3 of the drawings, each having a number of arms a projecting from one side and the projections or ears b from the opposite side. Each blank is also provided with the long arm c, which, 40 on the blank C', forms an extension of one of the ears b and in the blank C an extension of one of the arms a. The blanks are next rolled up into cylindrical form, the arms a being given a slight inward curve and the ears b being bent outwardly at right angles. The 45 sockets are then placed in the apertures B B' with the arms a of the socket C extending forward and those of the socket C' extending rearward. The ears extend over the edges 50 of the aperture and are clamped between the plates A A', said ears being turned so as to

be out of contact with each other and serving to hold the socket in fixed position and out of contact.

The arm c of the contact C passes through 55 an aperture B' in the plate A' and is connected with one of the electric conductors, while the arm c on the contact C' is connected with the other conductor.

D is the plug, comprising the following 60 parts: d is the end contact, which has a rounded point and a rearwardly-extending shank d', of reduced size, threaded at its end. Upon the shank is sleeved the insulating-collars e and f, between which is placed the hollow contact g, having a bearing on the two collars, holding it out of contact with the shank. 65

The contact g is provided with a shoulder h, in rear of which is the threaded shank i.

j are nuts engaging with the threaded portion 70 of the shank d and serving to clamp the parts together.

k is a flexible cord containing the two electric conductors, which are connected, respectively, to the shanks d' and i, preferably by 75 means of the sheet-metal fingers l and m, clamped in contact with said shanks and extending rearwardly. n is a tubular handle of insulating material, screwed upon the shank i.

A plug-switch thus formed is not only in- 80 expensive to construct, but is also very compact, as it is possible to place a very large number of the apertures B B' with their sockets C C' in a very small space, and as the arms c all extend to the rear of the board the connections are easily made. 85

The spring-arms a insure a good contact with the two contacts of the plug, while the ears b hold the sockets in position without possibility of touching each other. 90

What I claim as my invention is—

1. In a plug-switch the combination of two parallel insulator-plates apertured in line with each other, a spring-socket contact placed in each aperture and ears on said sockets extending between and clamped by said plates serving to hold said sockets in position out of contact with each other. 95

2. In a plug-switch, a spring-socket contact comprising a cylindrical body formed 100 from a sheet-metal blank and having the inwardly-curved spring-arms a projecting lon-

gitudinally from one end and the outwardly-bent ears *b* at the other end for the purpose described.

3. In a plug-switch the combination with two parallel insulator-plates apertured in line with each other of spring-socket contacts placed in said apertures, provided with the ears *b* extending between and clamped by said plates, serving to hold the sockets in position and out of contact with each other, and the inwardly-curved spring-arms *a* extending oppositely from said sockets.

4. In a plug-switch, the combination with the two parallel insulator-plates *A A'* having the apertures *B B'* in line with each other, and the apertures *B²* in the plate *A'* of the spring-socket contacts *C C'* placed respectively in the apertures *B B'*, each being provided with the ears *b* clamped between the

plates, and the oppositely-extending inwardly-curved arms *a*, and the arm *c* on the socket *C* extending through the aperture *B²*.

5. In a plug-switch, a plug comprising the end contact *d* having a rearwardly-extending shank *d'* of reduced size, threaded at its end, the insulating-collars *e f* sleeved upon said shank, the hollow contact *g* between having the shoulder *h* and threaded shank *i*, the nut *j* for clamping the parts together, the tubular handle *n* secured to the shank *i* and the flexible cord containing the electric conductors connected respectively to the shanks *d'* and *i*.

In testimony whereof I affix my signature in presence of two witnesses.

WILLIAM R. COLE.
